UNITED STATES PATENT OFFICE

172,874

ASH TRAY OR SIMILAR ARTICLE

Aubrey A. Gayle and Edna P. Gayle, Chicago, Ill.

Application August 26, 1953, Serial No. 26,585

Term of patent 14 years

(Cl. D85—2)

To all whom it may concern:

Be it known that we, Aubrey A. Gayle and Edna P. Gayle, both citizens of the United States, residing at Chicago, Illinois, have invented a new, original, and ornamental Design for an Ash Tray or Similar Article, of which the following is a specification, reference being had to the accompanying drawing, forming a part hereof.

Fig. 1 is a perspective view of an ash tray or similar article, showing our new design;

Fig. 2 is a top plan view thereof; and

Fig. 3 is a side elevational view thereof.

We claim:

The ornamental design for an ash tray or similar article, as shown.
